BRASSIERE

William Rosenthal, Bayville, N. Y.

Application July 22, 1955, Serial No. 37,099

Term of patent 14 years

(Cl. D20—4)

Fig. 1 is an elevational view of a brassiere showing my new design; and

Fig. 2 is a side perspective view.

The portion of the back not shown follows the lines shown in Fig. 2. The shoulder straps have been broken away in Fig. 2 for convenience of illustration.

I claim:

The ornamental design for a brassiere, as shown and described.
